UNITED STATES PATENT OFFICE.

FRANK ALBERT PARKER, OF SPENCER, IOWA.

FIRE-ESCAPE.

SPECIFICATION forming part of Letters Patent No. 785,019, dated March 14, 1905.

Application filed June 11, 1904. Serial No. 212,178.

To all whom it may concern:

Be it known that I, FRANK ALBERT PARKER, a citizen of the United States, residing at Spencer, in the county of Clay and State of Iowa, have invented new and useful Improvements in Fire-Escapes, of which the following is a specification.

This invention relates to fire-escapes, the object of the invention being to provide a portable fire-escape embodying a novel construction of a frictional rope-grip which will greatly facilitate and render safe the escape of a person from a burning building and his descent to the ground, the rope-grip being of such construction that while it acts with a frictional or binding grip on the rope, such gripping action may be easily regulated by the person descending, the construction of the grip being especially advantageous by reason of the fact that it may be grasped as a handhold without danger of the rope burning or chafing the hand of the person using the same.

With the above and other objects in view the invention consists in the novel construction, combination, and arrangement herein-after fully described, illustrated, and claimed.

In the accompanying drawings, Figure 1 is a perspective view of the fire-escape apparatus, showing the rope-grip, the manner of combining the rope therewith, and the means for supporting a sling, belt, or other body-supporting device. Fig. 2 is an enlarged detail view of the rope-grip.

Like reference-numerals designate corresponding parts in both figures of the drawings.

The frictional rope is composed of a bar or stock 1 of any suitable size and preferably round in cross-section. The stock 1 is provided with terminal eyes 2 and 3, which are considerably enlarged, as shown, and adapted to receive portions of a rope which is reeved therethrough, as shown in the figure.

Intermediate its ends the stock or bar 1 is provided with a central intersecting eye 5, which divides the stock into two equal straight parts. The said intermediate eye is made quite large, so as to provide oppositely-projecting semicircular offsets 6, which when the rope is

passed through the eye 5 always project considerably beyond the rope and form an efficient hand-grip, so that a person descending by means of the apparatus may steady himself by grasping the central portion of the stock, the said offsets 6 keeping his hands out of injurious contact with the rope as it runs through the intermediate eye. The central eye is arranged in reverse direction from the end eyes, so that the offsets thereof will extend laterally on opposite sides of the intersecting ends of the two parts of the stock.

The upper end of the rope 4 is secured to any suitable object in a room or hallway and the remainder of the rope thrown out of the window, the rope being long enough to reach to the ground. The frictional rope-grip is mounted on the rope so that the said rope passes downward through the upper eye 2, thence wrapping partially around the stock 1, passing through the eye 5, thence wrapping partially around the lower portion of the stock and passing through the lower eye 3. In order to obtain additional friction on the rope, it may be extended upward after passing through the eye 3 and carried again through the eye 2 and then downward, so that a person may grasp the grip with one hand and control the rapidity of descent by grasping the lower portion of the rope in the other hand and allowing the same to slip through the hand as he descends.

7 designates a snap-hook, which is attached by means of a suitable connection 8 to the lower eye 3 of the grip, said snap-hook being adapted to be engaged quickly with the sling or belt or analogous device secured about the body of the person using the apparatus.

The frictional rope-grip hereinabove described may be used in connection with any rope or flexible cable and enables a person to safely descend to the ground from any height and control the rapidity of descent. By making the intermediate eye large, and thereby providing the semicircular offsets, and placing said eye at right angles to the terminal eyes the rope is guided through the several eyes in such manner as to carry the same clear of the

hand which grasps the middle portion of the grip and bears directly upon the semicircular offsets.

Having thus described the invention, what 5 is claimed as new is—

A fire-escape embodying a stock having a central intersecting enlarged circular eye which serves to divide the stock, above and below the eye into two equal straight parts, 10 said parts having circular eyes on opposite ends, said central eye being arranged in re-

verse direction from the end eyes so that the offsets thereof will extend laterally on opposite sides of the intersecting ends of the two parts of the stock, substantially as specified. 15

In testimony whereof I affix my signature in presence of two witnesses.

FRANK ALBERT PARKER.
